CLAIM

The ornamental design for a medical robotic platform, as shown and described.

DESCRIPTION

1. Medical robotic platform

1.1 : Perspective

1.2 : Front

1.3 : Back

1.4 : Top

1.5 : Bottom

1.6 : Left

1.7 : Right

In the reproductions, the broken lines are for the purpose of illustrating portions of the medical robotic platform which form no part of the claimed design.
